SEYMOUR W. HILLIER, OF SULTAN, WASHINGTON, ASSIGNOR OF ONE-HALF TO JAMES HEADRICK, OF SULTAN, WASHINGTON

GUY-LINE TIGHTENER

Application filed September 17, 1928. Serial No. 306,454.

This invention relates to tighteners for guy lines, its object being the improvement in devices of this character to render the same more effective, reliable and convenient to regulate.

5 Another object is to provide a guy-line tightener which is capable of being quickly released without danger to the operator.

With the above and other objects in view, my improvements consist in the novel construction, adaptation and combination of parts hereinafter described and claimed.

In the accompanying drawing,—

Figure 1 is a side elevation of a guy-line tightener embodying my invention shown applied; Fig. 2 is a longitudinal vertical section of the tightener with a portion of a guy-line in side elevation; Fig. 3 is a plan view of Fig. 2, the guy-line being omitted; Fig. 4 is a transverse sectional view on lines 4—4 of Figs. 2 and 3; Fig. 5 is a perspective view of the removable gripping block; Fig. 6 is a similar view of the block-setting wedge; and Fig. 7 is a fragmentary side elevational view of an end of the tightener frame to illustrate the operation of the shackle releasing device.

In said drawing, the reference numeral 10 represents a cable constituting a guy-line for a post (not shown) and to which line the tightener is applied to couple it to a sling 11 whereby the guy-line is secured to an anchor, shown as a tree stump 12 in Fig. 1.

More specifically, the tightener comprises a frame consisting of two side plates 13 which, at one end of the frame, are connected by a saddle piece 14 whence the side plates extend upwardly and terminate in inwardly directed flanges 15 with a slot 16 therebetween as best shown in Fig. 4.

The slot 16 is of a width to permit the guy-line 10 being lowered through the slot into a channel 17 provided in the top of said saddle piece.

Positioned between the side plates 13 and below the flanges 15 of the frame is a removable block 18 and a wedge 19, one above the other. In the under surface of the block 18 at its midwidth is a groove 20 extending the entire length of the block, said groove being formed to provide a series of recesses 21 adapted to interfit with the strands of the guy-line.

The said block is provided with a plane upper surface upon which is seated the above mentioned wedge 19 which is adapted to operate between the frame flanges 15 and the block 18 to force the latter downwardly into engaged relation with the guy-line whereupon the block and saddle piece 14 coact to clamp the guy-line to the frame. The wedge is arranged to be actuated when driven in the direction of the cable pull as indicated by the arrow in Fig. 2. To prevent the wedge being accidentally dislodged, with the block 18, by the guy-line pull from the frame, the wedge is provided with means, such as horns 22, engageable with stop shoulders 23 of the frame to limit the outward movement of the wedge.

As shown, said wedge is provided with a lug 24 to extend through the slot 16, the portion of the lug protruding above the frame being intended to be struck at either end by a hammer as may be requisite for driving the wedge into or from its block setting relation. 25 represents reinforcing ribs to strengthen the end of the frame referred to against lateral distortion or breakage. At the other end of the frame from said saddle piece, the said plates are notched, as at 26, from below to receive the pin 27 of a clevis 28 whereby the tightener frame is connected to the looped extremities 11¹ of the anchor sling 11.

For releasably securing the clevis pin 27 within said notches of the frame I provide between the plates 13 a latch member 29 which is adapted to extend below said clevis pin and is connected to the frame plates 13 at diametrically opposite sides of said notches by a pivot bolt 30 and a detachable locking pin 31, respectively. Said latch member is further characterized by the provision of a finger extremity 32 which is adapted to serve as a lever arm against the clevis pin 27, as indicated in Fig. 7, to expel the clevis pin from the tightener frame by means of a hammer blow imparted against the other arm of the latch 29, as indicated by arrow in Fig. 7.

34 represents a pin engaged in both of the frame's side plates 13 and serves as the axle for a peripherally grooved wheel 35 which is disposed to have a projection of the

channel 20 tangential, or nearly so, with respect to the wheel groove.

The sole purpose of the wheel 35 is that of a pulley sheave to lead the free end 10¹ of the guy line 10 to the winding drum (not shown) of a donkey engine—either directly or through the medium of a rope attached to the guy-line—whereby the slack is taken from the guy-line and then rendered taut to be subsequently clamped to the tightener by means of the block 18 when actuated by the wedge 19.

For use, the end 10¹ of the guy-line 10 is threaded through the gullet 36 (Figs. 2 and 3) of the frame, and the main portion of the guy-line dropped, so to speak, through the frame slot 16 into the channel 20 which, being smooth—that is, not provided with corrugations—permits the guy-line being readily drawn by the above mentioned winding drum.

To apply the tightener, it is first connected, by means of the clevis 28 and sling 11, to the stump 12, or other suitable anchor; then the guy-line is inserted, as above explained in the tightener frame; then, after passing the guy-line about the sheave 35 as indicated by dotted line in Fig. 2, the guy-line is stretched.

The guy-line being thus stretched or drawn taut is coupled to the tightener frame by successively inserting the block 18 and driving the wedge into its place to cause the block to engage the guy-line. The guy-line being thus secured may now be liberated from the stretching or tensioning drum, its free end 10¹ falling upon the ground as represented in Fig. 1.

The guy-line may be released in two ways, namely: by disengaging the clevis pin 28 from the frame by means of the latch member 29 employed as a lever, as hereinbefore explained; or by retracting the wedge 19—by means of hammer blows imparted against the wedge projection 28—to free the block and permit its being drawn by means of the guy-line from the frame.

A quick release of the guy-line is attainable with either of the above described methods when the stress on the guy-line is moderate; but, when it is subjected to an excessive stress, the clevis ejecting way is preferable and more certain.

The invention is peculiarly useful in logging camps because of its safety, efficiency, and handiness.

What I claim, is,—

1. A guy line tightener, a rigid frame adapted to be secured to an anchoring device, said frame comprising a grooved saddle element and two plates extending upwardly from the sides thereof and terminating in flanges directed inwardly of the frame, a block adapted to be inserted in the frame between its side plates and having a groove formed to provide a series of recesses to inter-

fit with the strands of the guy-line, and a wedge arranged to be used in the frame between said flanges and the block for forcing the latter into guy-line clamping relation with respect to the frame.

2. In a guy-line tightener, a rigid frame having a saddle element and two plate elements extending upwardly from the opposite sides respectively of said saddle element and provided with flange elements disposed at the inner sides of the plates with respect to the frame, a removable block provided in the frame above the saddle element, said saddle element and the block being provided with opposing grooves to receive the guy-line, and a wedge adapted to be used in the frame between said flanges and the block for securing the frame and block in gripping relation with the guy-line.

3. In a guy-line tightener, a rigid frame having a saddle element and two plate elements extending upwardly from the opposite sides respectively of said saddle element and provided with flange elements disposed at the inner sides of the plates with respect to the frame, a removable block provided in the frame above the saddle element, and a wedge adapted to be used in the frame between said flanges and the block for securing the frame and block in gripping relation with the guy-line.

4. In a guy-line tightener, a rigid frame having a transverse section of a substantially U-shape, the side members thereof having inwardly directed flange elements, said flanges being spaced for the insertion therebetween of the guy-line into the frame, a block removably positioned within the frame, and a wedge adapted to be inserted endwise into the frame below said flanges for forcing the block into engaged relation with guy-line to effect the clamping of the latter to the frame.

5. In a guy-line tightener as defined in claim 4, wherein means are provided at one end of the wedge to engage the frame for limiting the movement of the wedge in one direction with respect to the frame.

6. In a guy-line tightener as defined in claim 4 wherein the wedge is provided with a lug element arranged to extend upwardly through the space between the frame flanges for the purpose of regulating the position of the wedge in either direction longitudinally of the frame.

7. A guy-line tightener comprising, in combination, a rigid frame provided at one end with means for clamping the guy-line to the frame, the other end of said frame being provided with a notch, a clevis having the pin element thereof engageable in said notch, and a latch device adapted to be used for retaining the clevis engaged within said notch and for ejecting the clevis therefrom selectively.

8. A guy-line tightener comprising, in combination, a rigid frame provided at one

end with a wedge actuated means for clamping the guy-line to the frame, the other end of said frame being provided with a notch, a clevis having the pin element thereof engageable in said notch, and a latch device adapted to be used for retaining the clevis engaged within said notch and for ejecting the clevis therefrom selectively.

9. In a guy-line tightener as defined in claim 7, wherein said latch is pivotally connected intermediate its length to the frame so as to afford two arms, one of the arms serving to secure the clevis to the frame and the other arm being adapted for use in displacing the clevis from the frame.

10. In a guy-line tightener, in combination, a frame provided in one end thereof with a wedge-controlled block to clamp the guy-line to the frame between the frame and the block, latch means provided at the other end of the frame for detachably connecting the frame securing devices thereto, and a sheave mounted in the frame for leading the free end of the guy-line.

25 Signed at Sultan, Washington, this 31st day of August, 1928.

SEYMOUR W. HILLIER.
